(57) **CLAIM**

I claim the ornamental design for a video recorder for vehicle, as shown and described.

DESCRIPTION

FIG. 1 is a perspective view of a video recorder for vehicle showing a new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a reference drawing that explains the state of use of the design.

The broken lines as shown in FIGS. 7-8 are for the purpose of illustrating the environmental structure and form no part of the claimed design. The broken lines as shown in FIGS. 3 and 5 are for the purpose of illustrating portions of the video recorder for vehicle that form no part of the claimed design.

1 Claim, 5 Drawing Sheets
